CLAIM

The ornamental design for a cesarean section scalpel, as shown and described.

DESCRIPTION

FIG. 1 is a top perspective view of a cesarean section scalpel.

FIG. 2 is a right side view thereof.

FIG. 3 is a left side view thereof.

FIG. 4 is a top view thereof.

FIG. 5 is a bottom view thereof.

FIG. 6 is a front view thereof.

FIG. 7 is a rear view thereof; and,

FIG. 8 is a right side view thereof in a condition of use. The broken lines shown in FIGS. 1-5 and FIG. 8 illustrate portions of the cesarean section scalpel that form no part of the claimed design. The additional broken lines shown in FIG. 8 illustrate environment and form no part of the claimed design.
